UNITED STATES PATENT OFFICE.

DAVID J. SEAMAN, OF SOUTH BEND, INDIANA.

DESIGN FOR FABRIC.

SPECIFICATION forming part of Design No. 34,494, dated May 7, 1901.

Application filed April 1, 1901. Serial No. 53,979. Term of patent 14 years.

To all whom it may concern:

Be it known that I, DAVID J. SEAMAN, a citizen of the United States of America, residing at South Bend, in the county of St. Joseph and 5 State of Indiana, have invented and produced a new and original Design for Fabrics, of which the following is a specification, reference being had to the accompanying drawing, which forms a part hereof.

10 This design relates to the ornamentation of cotton, silk, woolen, paper, celluloid, and other fabrics.

In the drawing I have shown a plan view of my design.

15 The leading feature of the design is the representation of a streamer of holly leaves and berries, arranged in bends or curves, with stars and bells in the alternate bends. The holly-leaves A form a continuous string or 20 streamer arranged in successive curves or

bends, which reverse alternately, and berries B appear interspersed between the leaves along the streamer. Stars C and a bell D appear within the area described by the alternate bends or curves of the streamer, and above the stars are ribbons E. The bell appears to be held by a ribbon F, and the ends of all the ribbons disappear within the streamer of leaves.

25 What I claim is—

30 The design for a fabric herein described and shown.

In testimony whereof I have signed this specification in the presence of two attesting witnesses.

DAVID J. SEAMAN.

Witnesses:

FRANK W. BAUDE,
THOMAS J. HANLON.
